UNITED STATES PATENT OFFICE.

NELSON MORRIS, OF WATERBURY, CONNECTICUT.

SPONGE-HOLDER.

SPECIFICATION forming part of Letters Patent No. 436,838, dated September 23, 1890.

Application filed October 7, 1889. Serial No. 326,236. (No model.)

To all whom it may concern:

Be it known that I, NELSON MORRIS, of Waterbury, in the county of New Haven and State of Connecticut, have invented new Improvements in Sponge-Holders; and I do hereby declare the following, when taken in connection with accompanying drawings and the letters of reference marked thereon, to be a full, clear, and exact description of the same, and which said drawings constitute part of this specification, and represent, in—

Figure 1 a side view of the holder in partial section, showing the sponge engaged; Fig. 2, a side view of the holding device detached.

This invention relates to an improvement in sponge-holders, and is particularly adapted for use in washing carriages or for other purposes where a continuous flow of water is desired, the object of the invention being to construct a holder which may be used without danger of injuring the carriage while washing and without wetting the hand of the operator; and it consists in the construction as hereinafter described, and particularly recited in the claim.

The holder consists of a tube A of a length sufficient to form a convenient handle, and is constructed with a collar B, which is internally screw-threaded to correspond to the standard thread on the male part of hose-couplings. At the other end of the said handle is a funnel-shaped projection C, within which the holding device is arranged, and as preferably constructed consists of two wires twisted together midway of their length and bent so as to form an eye D, as seen in Fig. 2, and from which the four ends extend diverging from the eye. The ends of the wires are pointed and are bent inward, forming four hooks a, as seen in Fig. 2. The holder

is placed in the funnel with its eye inward, the eye passing into the tube A, and so that the hooked ends of the wires shall be within the outer edge of the mouth of the funnel. It is secured in place by a screw E, passing transversely through the tube A and through the eye D, as seen in Fig. 1.

To introduce a sponge into the device the holder is removed and the sponge engaged with the hooks a and the holder reinserted into the mouth and secured, as above described. The device is then ready for use, and may be secured to the end of a hose in the same manner as the ordinary nozzle. The water passes through the tube and through the sponge. The sponge extends over the edges of the mouth, thereby preventing the metal portion from injuring the thing being washed.

To prevent the water from running over onto the tubular or handle portion A, as it would do were the device held in a nearly vertical position, a flange b is arranged around the tube below the funnel-shaped mouth c and so that the water passing down the outside of the mouth will be deflected and the handle will remain dry.

I claim—

A sponge - holder consisting of a tube adapted at one end to be secured to a hose-coupling and provided at the other end with a funnel, and a sponge-retaining device consisting of wires bent to form disengaging hooked arms for engagement with the sponge, and an eye for securing the device within the holder, substantially as described.

NELSON MORRIS.
